UNITED STATES PATENT OFFICE.

SIMEON B. HENDRICKS, OF ROCKFORD, ILLINOIS, ASSIGNOR TO EMERSON MANUFACTURING COMPANY, OF ROCKFORD, ILLINOIS.

HORSE HAY-RAKE.

SPECIFICATION forming part of Letters Patent No. 699,818, dated May 6, 1902.

Application filed September 3, 1901. Serial No. 74,192. (No model.)

To all whom it may concern:

Be it known that I, SIMEON B. HENDRICKS, a citizen of the United States, residing at Rockford, in the county of Winnebago and State 5 of Illinois, have invented certain new and useful Improvements in Horse Hay-Rakes, of which the following is a specification.

This invention relates to a class of horse hay-rakes in which the teeth are held down 10 in working position and just after they are released a connection is formed between the revolving axle and rake-head in order that the teeth may be raised to dump the load.

In the accompanying drawings, Figures 1 15 and 2 are perspective views of my improved horse hay-rake as seen from the front. Fig. 3 is a horizontal section of the clutch connection between the rake-head and axle.

The axle 1 supports the rake-head 2, and 20 teeth 3 are supported by the rake-head. The lengthwise angle-bars 4, 5, and 6 form the tongue and seat-supporting frame, which has a pivotal connection with the axle by the bracket 7 and other brackets. (Not shown.) The 25 rake-head 2 is pivotally supported by the axle by the bracket 8 and other brackets. (Not shown.) To the axle is secured a ratchet-wheel 9. A dog 10 has a pivotal connection at one end with a lever 11, and the lever has 30 a pivotal connection with the bracket 7. To the rake-head is secured a bracket 12, having a series of holes. To the angle-bar 5 are secured two brackets 13, which support a rock-shaft 14, the shaft having ears 15 and a 35 foot-lever 16 formed therewith. An arm 17 extends from the foot-lever, and a spring 18 forms a connection between this arm and the arm 11 of the clutch mechanism. One of the ears 15 has an extension 19, to which is connected a spring 20. Between the ears 15 is located a yoke 21 having a pivotal connection therewith. The lower end of this yoke has a rearward extension 22, which engages the under face of the angle-bar forming a stop 45 to the upward movement of the yoke.

A bracket 23 is secured to the angle-bar 6. A link 24 has a pivotal connection with the bracket intermediate its ends. One end of this link supports a foot-rest 25. The other 50 end has a pivotal connection with the links 26, and these links have a pivotal connection with the bracket 12. The pivotal point of connection between these links is located adjacent to the loop 21. A bail 27 has a pivotal

connection with the bracket and is provided 55 with a hooked extension 28, to which one end of the spring 20 is connected. The action of this spring 20 is to hold the link connection between the rake-head and tongue-supporting frame in lock against the loop 21, one end 60 of the spring exerting its force on the arm 19, thereby holding the stop of the loop against the angle-bar 5 and the other end of the spring exerting its force on the bail 27, which presses against the link 24, thereby forcing 65 its end connected to the links 26 up against the loop 21.

The parts shown in the drawings are in position for raking. When it is desired to dump the load, the attendant presses on the foot-lever 16, which will move the rock-shaft and move the loop down, which will break the lock connection between the rake-head and tongue-supporting frame. A further pressure on the foot-lever 16 will bring the dog 10 into engagement with the ratchet-wheel, thereby forming a connection between the revolving axle and rake-head, which will cause the teeth to be raised until the arm 11 strikes the stop 29, when the dog will be forced from its engagement with the ratchet-wheel and the rake-head liberated and allowed to drop into its working position, the spring 20 raising the loop 21 and returning the foot-lever to its former position and moving the link connection between the rake-head and tongue-supporting frame into lock. 85

I claim as my invention—

1. In a horse hay-rake, the combination of an axle, a rake-head, a tongue-supporting 90 frame, a double link connection between the rake-head and tongue-supporting frame, a foot-lever, a loop receiving the double link connection; a connection between the foot-lever and loop, and a stop for the loop. 95

2. In a horse hay-rake, the combination of an axle, a rake-head, a tongue-supporting frame, a double link connection between the rake-head and tongue-supporting frame, a foot-lever, a loop receiving the double link 100 connection, a connection between the foot-lever and loop, a stop for the loop, a pivoted bail and a spring connection between the bail and foot-lever.

SIMEON B. HENDRICKS.
